UNITED STATES PATENT OFFICE

139,347

DESIGN FOR AN AIR DIFFUSER OR THE LIKE

Carl A. Duffner, Cleveland, Ohio

Application July 14, 1943, Serial No. 110,664

Term of patent 7 years

(Cl. D62—4)

To all whom it may concern:

Be it known that I, Carl A. Duffner, a citizen of the United States, residing at Cleveland Heights, in the county of Cuyahoga and State of Ohio, have invented a new, original, and ornamental Design for an Air Diffuser or the like, of which the following is a specification, reference being had to the accompanying drawing, forming a part thereof.

Fig. 1 is a perspective view of an air diffuser or the like, showing my new design, and Fig. 2 is a side view of the same.

I claim:

The ornamental design for an air diffuser or the like, substantially as shown.

CARL A. DUFFNER.
